TOILET PAPER DISPENSER

Joseph Reganato, Brooklyn, N. Y.

Application June 4, 1935, Serial No. 24,975

7 Claims. (Cl. 242—56)

The invention relates to a paper dispenser and more especially to roll paper dispensers.

The primary object of the invention is the provision of a dispenser of this character, wherein a determined length of paper will be delivered and such length severed from the roll of paper as contained within the dispenser.

Another object of the invention is the provision of a dispenser of this character, wherein the determined length of paper severed from the roll, the severing being had automatically will be folded into a flat condition convenient for removal, the folding being automatically effected when the dispenser is operated.

Another object of the invention is the provision of a dispenser of this character, wherein the same is manually controlled and will deliver a determined amount of roll paper from it and such amount of paper separated from the roll of paper and automatically folded into compact form for delivery to a user.

A still further object of the invention is the provision of a dispenser of this character, which is simple in construction, thoroughly reliable and efficient in its operation, convenient for handling, adapted for hanging upon a wall or other support, strong, durable, and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is an elevation of the dispenser constructed in accordance with the invention with the casing shown in section on the line 1—1 of Figure 2.

Figure 2 is a sectional view taken approximately on the line 2—2 of Figure 1 with certain parts shown in elevation.

Figure 3 is a sectional view on the line 3—3 of Figure 2, showing the parts in reverse position.

Figure 4 is an enlarged fragmentary sectional view through the ratchet and spring of the driving mechanism of the dispenser.

Figure 5 is a sectional view on the line 5—5 of Figure 4 looking in the direction of the arrows.

Figure 6 is a fragmentary horizontal sectional view showing in detail the cutting knife or blade.

Figures 7, 8, 9 and 10 are fragmentary exploded detailed views illustrating the steps of feed of the paper and the final cutting of the same.

Similar reference characters indicate corresponding parts throughout the several views in the drawings.

Referring to the drawings in detail, the dispenser comprises a box-like body 10 preferably made from metal although it may be made from

any other material meeting the requirements and this body at its open back is closed by a hanger or bracket 11 which is suitably secured to a wall or other support so that the body can be hung therefrom, the bracket being attached to the body through removable fasteners 12 which are separably engaged both with the body and the bracket. Arranged interiorly of the body and supported at one side thereof is a housing 13 to which is fastened a roll arbor 14 for supporting the tubular coil 15 of a roll of strip paper 16, for example toilet paper. This roll 16 is introduced into the body 10 through a door opening in one side of said body, the door opening being closed by a swinging door 17 carrying a suitable latch or lock 18 so that it may be fastened in its closed position. The arbor 14 is located in the uppermost portion of the body 10.

Beneath the roll 16 and located approximately at the longitudinal center of the body 10 are the feed rollers 19 and 20, respectively, the latter being a guide roller while the roller 19 is a positively driven roller and their axles 21 are suitably journaled in the housing 13 and a second housing 22 within said body 10. The axle 21 of the roller 19 carries a gear 23 confined within the housing 13 and meshing with a driving gear 24, this being also within the housing 13 and is loose upon the hub 25 of a ratchet gear 26, its teeth 27 having coacting therewith a ratchet dog 28 pivoted at 29 to the gear 24 and spring tensioned at 30. This gear 26 has its hub 25 keyed or otherwise fixed to a driving shaft 31 extended exteriorly of the body 10 and carrying a hand crank 32 for manual control thereof.

The shaft 31 has fixed thereto a ratchet segment 33, this with the ratchet gear 26 being confined within the housing 13 and coacting with the segment 33 is a pivotal back check 34 which requires the segment 33 to be turned in one direction to the fullest extent thereof before the said segment 33 can be returned to normal or original position. The check 34 is pivoted to the body 10.

Pinned to the shaft 31 is a coiled clock spring 35 which is anchored at 36 and this spring automatically effects the return of the segment 33 to original or starting position after a complete stroke movement thereof is had. The return movement of the segment 33 is inactive on the gear 24 through the ratchet action of the ratchet gear 26 and dog 28 cooperating with each other.

Immediately beneath the feed rollers 19 and 20 is a horizontally swinging cutting blade or knife 37 which has a sweep across the path of feed of the paper of the roll 16 when passing between the feed rollers 19 and 20. The blade or knife 37 is pivoted at 38 and the other free end thereof protrudes into the path of a striker or actuator extension 39 on the segment 33 so that the blade or knife 37 is operated by this striker 39 to sever the

paper of the roll 16 when unwound therefrom of a determined length. The blade or knife 37 is returned to inactive position by a spring 40 after tripping the striker 39.

5 Below the knife or blade 37 within the body 10 is a substantially U-shaped folding frame 41, the closed side thereof at the center is formed with a hub 42 fitting a stud shaft 43 suitably journaled in the housing 22 and body 10. This shaft has 10 fixed thereto a gear 44 confined within the housing 22 and meshing with a gear 45 which is in mesh with a gear 46 on the axle 21 of the roller 19, these gears 45 and 46 being confined within the housing 22. As the paper is fed by the rollers 15 19 and 20 in a downward direction from the roll 17 the frame 41 folds the paper thereon until a predetermined length of paper has been folded whence the knife or blade 37 is automatically operated to sever this length of paper. The open 20 side of the frame 41 confronts a window 47 so that access may be had to the folded length of paper for the extraction thereof through the window 47 by a user of the dispenser.

The steps of feed of the paper when unwound 25 from the roll 16 by the rollers 19 and 20 are clearly demonstrated in Figures 7 to 10, inclusive, of the drawings.

The dispenser is manually operated by the crank handle 32 and on a complete stroke of 30 the segment 33 a determined length of paper will be unwound from the roll 16 and severed by the knife or blade 37 and also folded or wrapped upon the frame 41 whence it will be in a condition to be removed from the dispenser as clearly exhibited 35 in Figure 2 of the drawings.

The spring 35 functions to return the segment 33 to normal position or starting position and the check 34 prevents the return of the segment to this starting or original position excepting when 40 a complete operating stroke has been had by the segment.

What is claimed is:

1. In a dispensing device of the kind described, 45 a casing having a dispensing opening, a paper roll feed mechanism interiorly of the casing, means next to the feed mechanism and acting in the path of the feed thereof for severing a determined length of paper from the amount fed, and means for folding the severed paper at the location of the dispensing opening in a condition for hand delivery thereof through the said opening.

2. In a dispensing device of the kind described, 50 a casing having a dispensing opening, a paper roll feed mechanism interiorly of the casing, means next to the feed mechanism and acting in the path of the feed thereof for severing a determined length of paper from the amount fed, means for folding the severed paper at the location of the dispensing opening in a condition for hand delivery thereof through the said opening, and gearing operated by the paper roll feed mechanism for driving the folding means.

3. In a dispensing device of the kind described, 55 a casing having a dispensing opening, a paper roll feed mechanism interiorly of the casing, means next to the feed mechanism and acting in the path of the feed thereof for severing a determined length of paper from the amount fed, means for folding the severed paper at the location of the dispensing opening in a condition for hand delivery thereof through the said opening, gearing operated by the paper roll feed mechanism for driving the folding means, and means

operative by the paper roll feed mechanism for controlling the severing means.

4. In a dispensing device of the kind described, 60 a casing having a dispensing opening, a paper roll feed mechanism interiorly of the casing, means next to the feed mechanism and acting in the path of the feed thereof for severing a determined length of paper from the amount fed, means for folding the severed paper at the location of the dispensing opening in a condition for hand delivery thereof through the said opening, gearing operated by the paper roll feed mechanism for driving the folding means, means operative by the paper roll feed mechanism for controlling the severing means, and a support for 65 holding the paper for action thereon by the feed mechanism.

5. In a dispensing device of the kind described, 70 a casing having a dispensing opening, a paper roll feed mechanism interiorly of the casing, means next to the feed mechanism and acting in the path of the feed thereof for severing a determined length of paper from the amount fed, means for folding the severed paper at the location of the dispensing opening in a condition for hand delivery thereof through the said opening, gearing operated by the paper roll feed mechanism for driving the folding means, means operative by the paper roll feed mechanism for controlling the severing means, a support for holding the paper for action thereon by the feed mechanism, and means for resetting the severing means when moved from neutral non-cutting position.

6. In a dispensing device of the kind described, 75 a casing having a dispensing opening, a paper roll feed mechanism interiorly of the casing, means next to the feed mechanism and acting in the path of the feed thereof for severing a determined length of paper from the amount fed, means for folding the severed paper at the location of the dispensing opening in a condition for hand delivery thereof through the said opening, gearing operated by the paper roll feed mechanism for driving the folding means, means operative by the paper roll feed mechanism for controlling the severing means, a support for holding the paper for action thereon by the feed mechanism, means for resetting the severing means when moved from neutral non-cutting position, and manually controlled means for the 80 feed mechanism.

7. In a dispensing device of the kind described, 85 a casing having a dispensing opening, a paper roll feed mechanism interiorly of the casing, means next to the feed mechanism and acting in the path of the feed thereof for severing a determined length of paper from the amount fed, means for folding the severed paper at the location of the dispensing opening in a condition for hand delivery thereof through the said opening, gearing operated by the paper roll feed mechanism for driving the folding means, means operative by the paper roll feed mechanism for controlling the severing means, a support for holding the paper for action thereon by the feed 90 mechanism, means for resetting the severing means when moved from neutral non-cutting position, manually controlled means for the feed mechanism, and a ratchet acting means operated upon by the feed mechanism for intermittently moving the severing controlling means and automatically releasing the same at determined intervals for the operation of the resetting means.

JOSEPH REGANATO.
